(57) **CLAIM**

The ornamental design for a toe guard, as shown and described.

DESCRIPTION

FIG. 1 is a top front perspective view of a toe guard, showing my new design;

FIG. 2 is a top rear perspective view thereof;

FIG. 3 is a front elevation view thereof;

FIG. 4 the right-side elevation view thereof, the left-side elevation being a mirror image thereof;

FIG. 5 the top plan view thereof, the bottom plan being a mirror image thereof;

FIG. 6 is a rear elevation view thereof; and,

FIG. 7 is a top front perspective view of the toe guard, shown in a used condition.

The broken lines shown in FIG. 7 depicts environmental subject matter that forms no part of the claimed design.

The use of stippling indicates a contrasting appearance with the adjacent transparent portion of the toe guard; note, in FIGS. 2 and 6, the stippling is seen through a transparent rear portion.
